(No Model.)

S. G. PILLSBURY.

CORN SHELLER.

No. 380,767.

Patented Apr. 10, 1888.

UNITED STATES PATENT OFFICE.

SAMUEL GARVIN PILLSBURY, OF LONG ISLAND, KANSAS, ASSIGNOR OF
ONE-HALF TO ALICE V. WHITCOMB, OF SAME PLACE.

CORN-SHELLER.

SPECIFICATION forming part of Letters Patent No. 380,767, dated April 10, 1888.

Application filed August 30, 1887. Serial No. 248,293. (No model.)

To all whom it may concern:

Be it known that I, SAMUL GARVIN PILLSBURY, a citizen of the United States, residing at Long Island, in the county of Phillips and State 5 of Kansas, have invented a new and useful Improvement in Corn-Shellers, of which the following is a specification.

My invention relates to improvements in corn-shellers; and it consists in a device for 10 stacking the cobs after they have passed through the operation of shelling and are discharged from the sheller.

After the corn has been shelled from the cobs, if the latter are allowed to drop down 15 from the discharge-opening, they will soon accumulate in such quantities as to render the operation of the machine difficult. To obviate this trouble, carriers have been heretofore attached to the machine, under the said discharge-opening, and the cobs are conveyed by 20 this device to a distance and piled or stacked. The machinery for operating these carriers is often cumbersome, rendering the operation of the sheller very difficult; and it is to dispense 25 with all unnecessary friction that I have invented the herein-described device, whereby the cobs, as they pass out of the discharge-opening of the sheller, are struck by the wings of a revolving fan, which is operated by very 30 simple means, and thrown to a distance sufficient to prevent them from interfering with the operation of the machine.

In the accompanying drawings, Figure 1 is a perspective view of an ordinary corn-sheller 35 provided with one of my improved stackers. Fig. 2 is a detail view of the device detached.

Referring by letter to the drawings, A designates a corn-sheller of any ordinary form, having the usual interior construction, where- 40 by the ears of corn being passed in at one opening are shelled, the corn dropping into a receptacle under the device, the chaff being blown away by suitable fans, and the cobs dis- charged through an opening, B, in the front end 45 of the machine. This is all of the ordinary construction and arrangement, and need not be herein described in detail, as the same forms no part of the present invention.

C designates the operating crank of the 50 sheller, which is suitably connected to the interior machinery of the device; and D represents the fly-wheel, which is connected by suit-

able gearing with the shaft on which the said crank is mounted, so that the former is operated by the latter. A band-wheel, E, is secured 55 on the shaft of the fly-wheel, and for a purpose to be hereinafter explained.

G designates the base-plate of my device, which is secured on the front of the sheller, so that the opening or slot H therein aligns with 60 the opening B, through which the cobs are discharged. The said plate G is provided below the lower side of the opening B in the sheller with the forwardly-extending arms I I, provided with bearings in the ends. 65

K represents a shaft journaled in the said bearings, which are aligned, and on one end of the same is secured the band-wheel L, which is preferably much smaller than the band-wheel E on the shaft of the fly-wheel. 70

M designates the fan, secured on the shaft K, between the bearings, the said fan comprising the wings N N, disposed radially from the shaft as a center. The fans are constructed with the radial arms n n, disposed in pairs, and the trans- 75 verse-bars n' n', secured at the ends to the said radial arms. The wings are thus open and offer but little resistance to the air when rapidly rotated.

The band-wheels E and L are connected by 80 the belt or band O, so that when the shaft carrying the fly-wheel is rotated the shaft carrying the fan M will be rotated at a much greater speed, owing to the fact that the wheel L is much smaller than the wheel E. 85

The operation of the stacker will be obvious from the above. As the cobs are discharged from the opening B, they fall upon the rapidly-revolving fan M, the wings of which strike the cobs in succession and throw them from the 90 machine. Thus the cobs are piled or stacked without any trouble to the operator of the sheller, and the resistance offered by the skeleton fans is so slight as to be almost inappre- 95 ciable. There is no complicated machinery necessary to operate the stacker, and it may be applied to any sheller now in use at a very slight expense, as the same is very simple.

Having thus described my invention, I claim— 100

1. The combination, with a corn-sheller having a discharge-opening, B, in its end, of the plate G, secured to the body of the sheller, a fan mounted on said plate below the discharge-

opening B, and means for rotating said fan, substantially as set forth.

2. The combination, with a corn-sheller having the discharge - opening B and the band-wheel E attached to one of the revolving shafts of the sheller, of the base-plate G, secured to the sheller and having the outwardly-projecting arms I I, provided with bearings in the ends, the shaft K, mounted in the said bearings, the band-wheel L on the end of the shaft, the band or belt O connecting the said band-wheels E and L, and the fan M, secured to the shaft K between the bearings, all constructed and arranged substantially as and for the purpose specified.

3. The combination, with a corn-sheller having the discharge - opening B and the band-wheel E attached to one of the revolving shafts of the sheller, of the base-plate G, secured to the body of the sheller, and having the opening H therein to align with the opening B, the

arms I I, secured to the said plate and having bearings therein, shaft K, mounted in the bearings and having the band-wheel L on the end connected to the band-wheel E by the belt O, 25 and the fan M on the shaft K, comprising the radial arms n n, arranged in pairs, and the transverse bars n' n', secured at the ends to the said radial arms, the said fan being arranged below the discharge-opening B, whereby, as 30 the cobs drop therefrom after having passed through the sheller, the wings of the rapidly-rotating fan strike the same, as and for the purpose hereinbefore specified.

In testimony that I claim the foregoing as my 35 own I have hereto affixed my signature in presence of two witnesses.

SAMUEL GARVIN PILLSBURY.
